UNITED STATES PATENT OFFICE.

DAVID W. CHALMERS, OF SPRINGFIELD, ILLINOIS.

WATCH-REGULATOR.

SPECIFICATION forming part of Letters Patent No. 269,385, dated December 19, 1882.

Application filed September 9, 1882. (No model.)

To all whom it may concern:

Be it known that I, DAVID W. CHALMERS, a citizen of the United States, and a resident of Springfield, in the county of Sangamon and State of Illinois, have invented a new and valuable Improvement in Watch-Regulators; and I do hereby declare that the following is a full, clear, and exact description of the construction and operation of the same, reference being had to the annexed drawings, making a part of this specification, and to the letters and figures of reference marked thereon.

Figure 1 of the drawings is a plan view of my device, and Fig. 2 is a vertical sectional view.

This invention has relation to an improvement on the micrometer watch-regulator described in Letters Patent No. 229,215, dated June 22, 1880; and it consists in the construction and novel arrangement of parts, as will be hereinafter fully described and claimed.

In the accompanying drawings, the letter *a* designates the watch-plate, and *b* a circular recess therein, having an offset-recess, *c*, in communication with its outer portion.

d represents a disk, which is seated in the recess *b*, said disk being provided with teeth *e* to engage an operating-pinion, *g*, which is seated in the offset-recess *c*. The stem or post of the pinion is rigidly connected thereto, and is provided with a head, *h*, which is squared or slotted, so as to be easily turned with an appropriate instrument.

k indicates a tribranched arc-plate, which is located across the recess *b* and over its disk, and has an arm, *l*, extending over the offset *c*

and its pinion. In the arm *l* is formed a perforation serving as a seat or bearing for the upper journal portion of the pinion-stem, and in the body of the arc-plate is formed a bearing for the upper journal of the disk *d*. The arc-plate is graduated at *m*. A swivel-connection, *s*, is pivoted to that portion of the disk which is nearest the center of the watch-plate, and this connection is engaged by the regulator arm or pointer *p*, to which the balance-spring is connected. By turning the pinion *g* a positive motion is given to the disk *a* and communicated thereby to the arm or pointer *p*. When said arm has been adjusted its position is maintained in a positive manner by the toothed connection between the disk and pinion.

Having described this invention, what I claim, and desire to secure by Letters Patent, is—

The toothed disk *d*, seated in a circular recess, *b*, of the watch-plate, having an offset-recess, *c*, holding the toothed operating-pinion *g*, and the tribranched graduated arc-plate *l*, spanning the disk-recess and extending over the offset-recess, and forming the upper bearings for the disk and pinion, in combination, substantially as specified.

In testimony that I claim the above I have hereunto subscribed my name in the presence of two witnesses.

DAVID WILLIAM CHALMERS.
